E. H. LAWS,
PLATE ATTACHING MEANS,
APPLICATION FILED FEB. 24, 1920.

1,394,029.

Patented Oct. 18, 1921.

UNITED STATES PATENT OFFICE.

EDWARD H. LAWS, OF CINCINNATI, OHIO, ASSIGNOR TO THE GUSTAVE FOX COMPANY, OF CINCINNATI, OHIO, A CORPORATION OF OHIO.

PLATE-ATTACHING MEANS.

1,394,029.

Specification of Letters Patent.

Patented Oct. 18, 1921.

Application filed February 24, 1920. Serial No. 361,051.

To all whom it may concern:

Be it known that I, EDWARD H. LAWS, a citizen of the United States, residing in Cincinnati, in the county of Hamilton and State 5 of Ohio, have invented certain new and useful Improvements in Plate-Attaching Means, of which the following is a specification.

My invention relates more particularly to means for attaching name plates to shells of 10 automobile radiators, but may be used for fastening plates to other objects and for other purposes.

Heretofore, trademark name plates have been applied to radiator shells by means of 15 bolts, nuts and washers, whereby the plates were held upon the radiator shell by friction and it was necessary in such construction to apply the plate to the shell before the shell and other parts of the radiator were assembled. 20 These plates are usually highly finished with enamel, varnish or nickel which is liable to be marred if secured to the radiator shell before it is assembled with the other parts of the radiator.

25 The objects of my invention are to provide simple, convenient and efficient means for securely and permanently fastening the name plate to the shell after the radiator shell and other parts of the radiator have been assembled so as to avoid damage to the 30 plate and to permit the plate to be thus attached after the automobile is otherwise completely finished, ready for shipment, and to conceal the attaching means from view, as 35 well as from access to thereby prevent the removal of the name plate.

My invention consists in the parts and in the combination and arrangement of parts as herein set forth and claimed.

40 In the drawings:

Figure 1 is a front view of a radiator shell or other base, slotted ready to receive my attachment;

45 Fig. 2 is a vertical section of the name plate, tongue, shell and coupling pin on the line 2—2 of Fig. 3;

Fig. 3 is a rear view of the plate, tongue, radiator shell and coupling pin;

50 Fig. 4 is a perspective view of the coupling pin;

Fig. 5 is a rear perspective view of the radiator shell showing a modified construction;

Fig. 6 is a section on the line 6—6 of Fig. 7;

Fig. 7 is a rear view of the name plate 55 with attached tongue, radiator shell and coupling pin illustrating a modified construction;

Fig. 8 is a perspective view illustrating a modified construction of either single or 60 double tongue;

Fig. 9 is a transverse section on the line 9—9 of Fig. 5;

Fig. 10 is a rear view of the radiator shell or base showing another form of slot; 65

Fig. 11 is a perspective rear view of the name plate with attached tongue adapted to be used with the slotted shell shown in Fig. 10;

Fig. 12 is a perspective view of the coupling pin used in connection with the slot shown in Fig. 10, and the tongue shown in Fig. 11; 70

Fig. 13 is a perspective view showing the parts represented in Figs. 10, 11 and 12 assembled in position to lock the name plate 75 on the base; and Fig. 14 is an edge view.

In the embodiment of my invention as 80 illustrated in Figs. 1 to 4 inclusive, tongue 1 has slot 2 provided with an enlarged coupling pin receiving opening 3 at its top. Said slot is curved rearwardly to form shoulder 4 to support coupling pin 5 in elevated position while the parts are being assembled, said slot inclining downwardly and for 85 wardly toward the bottom of tongue 1 to receive coupling pin 5 which is reduced to form a circumferential channel 6 between its ends thereby forming cylindrical heads 7 and 8. Tongue 1 is soldered or otherwise se 90 cured in groove 9 in the rear wall of name plate 10 and when thus secured, the lower end of slot 2 extends into close proximity to said plate. The radiator shell or other base 11, is provided with a Greek cross-shaped slot 12 adapted to receive tongue 1 and coupling pin 5 resting upon shoulder 4 and when said tongue is so inserted, the coupling pin will drop down in slot 2 and form a wedge, its central reduced part 6 bearing 95 100

against wall *a* of slot 2 and its heads 7 and 8 bearing against the rear wall 13 of radiator shell or other base 11, thereby securely fastening said name plate 10 against accidental 5 or intentional removal or displacement.

It will be apparent that my invention is capable of some modification without departure from the spirit or scope thereof, as for instance, the construction may be modified as illustrated in Figs. 5 to 7 inclusive, in which the shell or base 11' is provided with a slot 12' having vertically disposed rearwardly extending flanges 14 curved at the top and of gradually increasing width 10 from top to bottom and also spaced apart from each other in gradually increased distance from top to bottom, and in which the plate 10 is provided with bifurcated tongue 1' secured thereto and having slot 2' slanting 15 downwardly away from said plate through each wing 16 of said tongue, and having an enlarged opening 3' at its top to receive coupling pin 5' which is adapted to rest on shoulder 4' when the parts are 20 being assembled. In this construction, pin 5' having heads 7' and 8' and reduced portion 6', is first inserted through opening 3' where it rests upon shoulder 4' and said coupling pin together with the bifurcated 25 tongue 1' is inserted into slot 12' whereupon the coupling pin will drop by gravity to the position shown in Fig. 7 and thereby 30 securely lock the name plate in position upon the base.

Fig. 8 shows a slightly modified form of tongue 1'' from that shown in Figs. 2 and 6 and it may be employed either with a single tongue or a bifurcated tongue. Fig. 14 is an edge view of the tongue shown in 35 Fig. 8, and shows the part *b* thereof sprung slightly to one side of the flat face of the tongue to insure a close fit between the tongue and the wall of slot 12'' in order to prevent rattling of the parts. This form 40 of tongue is illustrated in Fig. 11 where it is shown mounted in groove 9 of plate 10 and is adapted to receive coupling pin 5'' (Fig. 12) and to be inserted in slot 12'' shown in Fig. 10, the parts illustrated in 45 Figs. 10, 11 and 12 being assembled as shown in Fig. 13. This construction of coupling pin is provided with heads 7'' and 8'' and with reduced parts 6''. The slot 2'' is provided with enlarged receiving 50 opening 3'' and shoulder 4''. The parts in this construction are assembled in the same manner as shown and described with reference to the several parts illustrated in 55 Figs. 1 to 4 inclusive.

In all of these constructions the coupling pin is inserted in an enlarged opening at the top and rests upon a shoulder while the tongue of the plate is being inserted through the slot of the shell or base and after the 65 tongue is inserted the pin will drop by

gravity and securely wedge the parts together and hold the name plate in permanent position upon the shell, thereby preventing either accidental or intentional removal of the plate.

What I claim as new and desire to secure by Letters Patent is:

1. In plate attaching means, a plate, a tongue secured thereon at right angles thereto and having a vertically inclined slot 75 therein extending downwardly toward said plate at an acute angle, a coupling member adapted to be inserted in said slot and projecting to each side of said tongue, and a base having a slot to receive said tongue 80 and coupling member whereby said coupling member is adapted to wedge itself between said tongue and base to bind said plate to said base.

2. In plate attaching means, a name plate, 85 a tongue mounted thereon and having a slot therein, a coupling pin adapted to be inserted in said slot, a base having a slot 90 therein and adapted to receive said tongue and coupling pin, whereby said pin is adapted to be moved downwardly in said slotted tongue to form a wedge between the wall of said tongue and the wall of said base whereby said plate is securely fastened to said base.

3. In plate attaching means, a plate having a vertical groove in its rear wall, a tongue secured in said groove and having an inclined slot extending transversely through said tongue, a coupling pin having 100 a cylindrical head upon each end, a base having a vertical slot to receive said tongue and a transverse slot to receive said coupling pin whereby when said tongue and said coupling pin are inserted in said slots said pin will be adapted to be moved downwardly in the tongue whereby the heads of said coupling pin will bear against the wall of said base and its reduced central part will bear against the rear wall of the tongue slot, 110 thereby forming a wedge whereby said plate is permanently held in position upon said base.

4. In plate attaching means, a name plate having a plurality of slotted tongues mounted thereon, a coupling pin adapted to be inserted transversely through said slotted tongues and a slotted base adapted to receive said tongue and said coupling pin whereby said pin is adapted to be moved downwardly in said slotted tongue in wedging engagement with said base and said tongue whereby said plate is securely held in position upon said base.

5. In plate attaching means, a name plate, 125 a tongue secured thereon, and having a slot formed with an enlarged part at its top and curved outwardly away from said name plate adjacent said enlarged part to form a shoulder and extending downwardly at an 130

acute angle toward said name plate, a coupling pin adapted to be inserted transversely in said enlarged part of said slot and to rest upon said shoulder, and a slotted base 5 adapted to receive said tongue and coupling pin whereby said pin is adapted to be moved downwardly in said slot and act as a wedge to bind said plate and base together.

6. In plate attaching means, a base having a slot, a name plate having a slotted tongue thereon and having a part of said tongue extending out of the plane of the side of said tongue to closely fit the wall of said slot and separate means for coupling said base and plate together.

EDWARD H. LAWS.
